UNITED STATES PATENT OFFICE.

EUGENE AMBROZY, OF NEW YORK, N. Y.

CONSTRUCTION OF MARINE VESSELS.

1,168,926.

Specification of Letters Patent. Patented Jan. 18, 1916.

Application filed May 11, 1915. Serial No. 27,855.

To all whom it may concern:

Be it known that I, EUGENE AMBROZY, a subject of the King of Hungary, and a resident of the city of New York, in the county 5 of New York and State of New York, have invented certain new and useful Improvements in Construction of Marine Vessels, of which the following is a specification.

The present invention relates to marine 10 vessels, or in other words to ships.

The main object of the invention is to produce a vessel that is provided with means for preventing it from sinking, involving impenetrable or puncture-proof skins or sides, 15 and also the provision of a "double" hull.

Another object of the invention is to combine lightness of construction with great strength and resistance to any tendency to longitudinal bending or buckling to which 20 vessels are ordinarily subjected.

A further object of the invention is to provide the vessel with a triple bottom, which bottoms are so interconnected and united with a longitudinal bulk-head and 25 the transverse frames of the vessel that a staving in of the outermost bottom is rendered almost impossible, or, if a hole should be burst into the said outermost bottom, the damaged area will be confined, due to the 30 connections above mentioned, to a possible minimum.

A still further object of the invention is to produce simple and efficient bracing means between the two hulls of the vessel.

35 A further object of the invention is the provision of a novel construction of the sides, including also the bottom, of the vessel which renders the same puncture-proof irrespective of the type or character of the sheathing or 40 planking.

With these and other objects in view, which will more fully appear as the nature of the invention is better understood, the same consists in the combination, arrangement and construction of parts hereinafter 45 fully described, pointed out in the appended claims and illustrated in the accompanying drawings, it being understood that many changes may be made in the size and proportion 50 of the several parts and details of construction within the scope of the appended claims without departing from the spirit or sacrificing any of the advantages of the invention.

55 One of the many possible embodiments of

the invention is illustrated in the accompanying drawings, in which:—

Figure 1 is a transverse section taken midship of a vessel constructed in accordance with the present invention, the right side of 60 said section being shown incomplete in order to more clearly show the construction; Fig. 2 is a section taken on line 2—2 of Fig. 1, the said section showing only a portion of the vessel including its bow part; Fig. 3 is a 65 similar section taken on line 3—3 of Fig. 1; Fig. 4 is a section taken on line 4—4 of Fig. 1, on a larger scale, of a portion of the vessel; Fig. 5 is an enlarged detail section of the lower portion of the structure shown 70 in Fig. 1; Fig. 6 is a section taken on line 6—6 of Fig. 5; Fig. 7 is a section taken on line 7—7 of Fig. 5; Fig. 8 is a transverse section taken through a portion of the vessel, on an enlarged scale, showing the bracing 75 means between the two hulls thereof; Fig. 9 is a section taken on line 9—9 of Fig. 8; Fig. 10 is a section taken on line 10—10 of Fig. 9; Fig. 11 is a section taken on line 11—11 of Fig. 9; Fig. 12 is a perspective 80 view of one of the longitudinal stringers between the bottoms of the vessel; Fig. 13 is a vertical section showing the connection between the deck beams and the longitudinal bulk head of the vessel; Fig. 14 is a section 85 taken on line 14—14 of Fig. 13; Fig. 15 is a section taken on line 15—15 of Fig. 13; Fig. 16 is a vertical section taken through the connection between the deck beams and the transverse frames of the inner hull of the 90 vessel; Fig. 17 is a section taken on line 17—17 of Fig. 16; Fig. 18 is a section taken on line 18—18 of Fig. 16; and Fig. 19 is a section taken on line 19—19 of Fig. 16.

In the drawings, the numeral 20 indicates 95 the keel of the vessel, extending, as in all structures of this type, throughout the length of the vessel, and being made in the form of an I-beam, the lower flange 21 of which is wedge-shaped in cross section for 100 the well known purpose. A continuation of the keel is formed by a stem 22 in the bow part of the vessel, as clearly shown in Figs. 2 and 3 of the drawings, and by a corresponding member in the stern part of the 105 vessel (not shown in the drawings). Above the keel is disposed a vertical bulk-head 23, extending from stem to stern and connected with the transverse frames of the vessel in a manner hereinafter to be described. This 110

bulk-head divides, generally speaking, the hull into two longitudinal compartments. The bulk-head is provided with door-ways 24 (Fig. 4), which may be closed by doors of any suitable type in the well known manner.

- 10 The transverse frames of the vessel are each made of two substantially L-shaped plates 25, the outer contours of which correspond, of course, to the respective transverse cross sections of the vessel. These plates, which form the back-bones of the transverse members, are disposed at suitable distances from each other and are united with auxiliary transverse frames, each comprising a pair of plates 26, the heights of which extend only one or two floors or decks above the bottoms, while the plates 25 extend to the uppermost deck of the vessel. The outer edges of the plates 25 and 26 are 20 provided with substantially equidistantly arranged, parallel slots 27, the slots of the several plates being in alinement with each other for a purpose hereinafter to be described. These slots run at right angles to 25 the edge of a plate where said edge is straight, and in radial direction to the curve where said edge is curved, as for instance at the bilge. Parallel to the outer edge of each plate 25 and adjacent to the slotted portion 30 thereof is riveted to each face of the same a channel-iron 28, for instance of U-shape cross section, said channel-irons extending into the spaces formed between the flanges of the keel and forming, together with the plates 35 25, the transverse frames of the outer hull of the vessel. In a similar manner are riveted to both faces of the plates 26 channel-irons 29, constituting with the plates 26 auxiliary transverse frames. The main and 40 auxiliary transverse frames are spaced apart by channel-irons 30, which abut against the keel and are riveted to the latter, and also connected by the intermediary of channel-irons 31 with the channel-irons 28 and 29.
- 45 A substantial distance above the channel-irons 28 and 29 there are riveted to both faces of each of the plates 25 and 26 channel-irons 32, said last named channel-irons resting upon the upper flange of the keel and extending toward the sides of the vessel and thence upward, their outer ends being attached in any suitable manner to the channel-irons 28 and 29. The channel-irons 32 are spaced apart by longitudinal channel-irons 33, which abut against and are attached to the bulk-head 23 and to the said channel-irons 32. Inclined braces 34, in the form of channel-irons, are riveted to both faces of the plates 25 and 26, their lower 55 ends being connected with the channel-irons 32 near to the inner ends of the latter, and the upper ends of the said braces being suitably connected to the channel-irons 28 and 29, respectively.
- 60 65 In parallel relation to and flush with the

inner edges of the plates 25 are riveted to both faces of the latter channel-irons 35, resting upon and being attached to the braces 34, and forming with the latter the transverse frames of the inner hull of the vessel. 70

The channel-irons 32 are supported by stringers 36, made in the form of composite I-beams, which rest upon the transverse frames 28 and 29. Struts 37 connect the channel-irons 32 with the transverse frames 75 28 and 29 to further brace and strengthen the elements. The stringers 36 extend through the plates 25 and 26.

The skin of the outer hull of the vessel is constructed in the following manner: To 80 both faces of each of the plates 25 and 26, and between the slots 27 therein, are attached angle-irons 38, which are bent into substantially U-shape, each of said angle-irons being disposed between two slots in the 85 said plates and having a flange 39, that is disposed at right angles to the plane of the respective plate. U-shaped stringers 40 have their flanges 41 disposed in the slots 27, to wit: In each slot there are disposed the 90 flanges of two adjoining stringers, their bases 42 being riveted to the flanges 39 of the angle-irons 38. In this manner the hull is provided with an outer skin, that is practically impenetrable. These stringers are 95 covered by a sheathing 43 of any suitable material. To properly brace the stringers 40 there run in parallel relation to the channel-irons 28 angle-irons 44, carrying in alinement with the angle-irons 38 substantially 100 U-shaped brackets 38', which are in engagement with and attached to the stringers 40.

The vessel may be provided with any suitable number of decks, each of which is formed by deck-beams 45, the inner ends of which are footed on stringers 46, which are attached to the bulk-head 23, while their outer ends are connected by angle-irons 47, or similar means, with the channel-irons 35. To properly brace and space apart the transverse frames 35, stringers 48 are attached to adjacent frames, said last named stringers being disposed level with the respective deck beams. 110

Struts 49 connect the angle-irons 32 with 115 one set of stringers 46, and struts 50 the angle-irons 34 with another set of stringers 46, said struts serving to keep, in addition to the elements hereinabove mentioned, the said angle-irons in proper position in relation to the longitudinal bulk-head 23 both against inner and outer pressure. Inasmuch as the sides of the outer hull and the angle-irons 32, which form, as will hereinafter appear, one of the bottoms of the vessel, are 120 connected with the bulk head, the pressure, to which they are subjected, is transferred to and taken up by the bulk head.

The angle-irons 35 and 34 serve as a support for an inner sheathing 51. To the un- 125

derfaces of the upper flanges of the angle-irons 32 is riveted a sheathing 52, thereby forming an intermediate bottom of the vessel between the bottoms of the outer and inner hull thereof.

5 The deck-beams 45 are united by longitudinal stringers 53, which are braced by diagonal struts 54. The connection between the inner end of the deck beams and longitudinal bulk-head 23 is, preferably, made by channel-irons 55, which run from deck-beam to deck-beam and are attached to the latter and to the bulk-head. Below the inner end of each deck-beam 45 is disposed a post 56, 10 for instance in the form of an angle-iron, that is properly attached to the upper and lower flanges of the respective stringer 46.

Immediately below each deck-beam is located between the outer and inner hulls a 20 bracing girder 57, comprising in the case illustrated in the drawings a plurality of horizontal plates 58, which are united, for instance, by transverse I-beams 59. Each girder extends from plate 25 to plate 25, and 25 is supported by keelsons 60, for instance in the form of U-shaped beams, which are suitably attached to the channel-irons 28 on the plates 25. The inner ends of these girders are secured, for instance, by angle-iron 61, 30 to the sheathing 51. Flush with the deck beams 45 are attached to the channel-irons 28 beams 62, resting upon the uppermost plates of the girders 57, and being connected with the transverse beams 63, that are attached to the sheathing 51 and form continuations of the deck beams 45. The deck beams 45 and 63 are covered by a suitable 35 deck plating 64, in which may be provided the necessary hatches, etc., as usual.

40 From the foregoing it appears that the vessel comprises an inner hull and an outer hull, in combination with three bottoms, the several decks between the inner and outer hulls constituting longitudinal water-tight 45 compartments. The outer skin, being composed of stringers which are in abutment with and properly attached to each other, form an impenetrable wall. Should the outer bottom be injured, water will not reach 50 the lowermost deck, there being still two bottoms to be penetrated. Inasmuch as the second bottom is properly braced and armored, as it were, by the stringers 36 and struts 37, it is almost impossible to stave in 55 the same. The two hulls, being braced by the girders 57 and connected by the plates 25 and 26, cannot separate.

The outermost bottom of the vessel may be filled with reinforced concrete up to the 60 upper flanges of the channel-irons 28 and 29 to lend the same the required rigidity.

Attention is called to the fact that the plates 25 and 26 are provided with registering openings 65, whereby in the manner 65 above described only longitudinal water-

tight compartments are formed between the inner and outer hulls of the vessel. It is to be observed, however, that if these openings were not left, these compartments would be subdivided into a plurality of transverse 70 compartments.

What I claim is:—

1. An iron vessel comprising an outer and an inner hull having a common keel, a longitudinal bulk-head resting upon said keel, 75 transverse plates fastened to said keel, channel-irons disposed along the outer edges of said plates and attached to the latter and to said keel, thereby constituting the transverse frames of said outer hull, a second set of 80 channel-irons secured to said plates and said bulkhead, thereby forming the transverse frames of said inner hull, deck-beams held upon said bulk-head and the transverse frames of said inner hull, and bracing girders between the two hulls. 85

2. An iron vessel comprising an outer and an inner hull having a common keel, a longitudinal bulk-head resting upon said keel, 90 transverse plates fastened to said keel, channel-irons disposed along the outer edges of said plates and attached to the latter and to said keel, thereby constituting the transverse frames of said outer hull, a second set of 95 channel-irons secured to said plates and said bulkhead, thereby forming the transverse frames of said inner hull, deck-beams held upon said bulk-head and the transverse frames of said inner hull, and bracing girders attached to the skin of the inner hull 100 and to the transverse frames of the outer hull. 105

3. An iron vessel comprising an outer and an inner hull having a common keel, an intermediate bottom disposed between the bottoms of said two hulls, a longitudinal bulk head resting upon said keel, transverse plates fastened to said keel, channel-irons disposed along the outer edges of said plates and attached to the latter and to said keel, 110 thereby constituting the transverse frames of said outer hull, a second set of channel-irons secured to said plates forming the transverse frames of said inner hull, and struts carried by said plates and attached 115 to said intermediate bottom and said bulk-head.

4. An iron vessel comprising an outer and an inner hull having a common keel, an intermediate bottom disposed between the bottoms of said two hulls, a longitudinal bulk head resting upon said keel, transverse plates fastened to said keel, channel-irons disposed along the outer edges of said plates and attached to the latter and to said keel, thereby 120 constituting the transverse frames of said outer hull, a second set of channel-irons secured to said plates forming the transverse frames of said inner hull, struts connecting 125 said intermediate bottom with said bulk-head. 130

head, and struts between the bottom of the inner hull and said bulk-head, said struts being carried by said plates.

5. An iron vessel comprising an outer and an inner hull having a common keel, a longitudinal bulk-head resting upon said keel, transverse plates fastened to said keel, channel-irons disposed along the outer edges of said plates and attached to the latter and to 50
 10 said keel, thereby constituting the transverse frames of said outer hull, a second set of channel-irons secured to said plates and said bulkhead, thereby forming the transverse frames of said inner hull, deck-beams 55
 15 held upon said bulk-head and the transverse frames of said inner hull, and bracing girders between the two hulls, said bracing girders dividing the space between said two hulls into longitudinal water-tight compartments.

6. An iron vessel comprising an outer and an inner hull having a common keel, an intermediate bottom disposed between the bottoms of said two hulls, a longitudinal bulk 60
 25 head resting upon said keel, transverse plates fastened to said keel, channel-irons disposed along the outer edges of said plates and attached to the latter and to said keel, thereby constituting the transverse frames of said 65
 30 outer hull, a second set of channel-irons secured to said plates forming the transverse frames of said inner hull, struts carried by said plates and attached to said intermediate bottom and said bulk-head, and stringers 70
 35 resting upon the bottom of said outer hull and supporting said intermediate bottom, said last named stringers extending through 75
 said plates.

7. An iron vessel comprising a keel, transverse plates attached to said keel having slots in their outer edge portions, channel-irons disposed in parallel relation to the outer edges of said plates and attached to said keel, thereby constituting the transverse 80
 40 frames of the hull, said slots running from the outer edges of said plates to the channel- 85
 45

irons thereon, U-shaped stringers having their flanges disposed in the slots of said plates and in abutment with said channel-irons, thus forming the skin of the hull, the 50
 abutting flanges of each adjacent pair of stringers being disposed in a common slot, means for fastening said stringers to said plates, and a sheathing secured to said stringers. 55

8. An iron vessel comprising a keel, transverse plates attached to said keel having slots in their outer edge portions, said slots running at right angles to the edge where such edge is straight and radially where 60
 such edge is curved, channel-irons disposed in parallel relation to the outer edges of said plates and attached to said keel, thereby constituting the transverse frames of the hull, said slots running from the outer edges 65
 of said plates to the said channel-irons thereon, U-shaped stringers having their flanges disposed in the slots of said plates and in abutment with said channel-irons, thus forming the skin of the hull, the abutting flanges of each adjacent pair of stringers being disposed in a common slot, means for fastening said stringers to said plates, and a sheathing secured to said stringers. 70

9. An iron vessel comprising an outer and 75
 an inner hull having a common keel, a longitudinal bulk-head resting upon said keel, transverse plates fastened to said keel, channel-irons disposed along the outer edges of 80
 said plates and attached to the latter and to said keel, thereby constituting the transverse frames of said outer hull, a second set of channel-irons secured to said plates and said bulk-head, thereby forming the transverse frames of said inner hull, and struts 85
 carried by and attached to said plates and said bulk-head.

Signed at New York, in the county of New York, and State of New York, this 10th day of May, A. D. 1915.

EUGENE AMBROZY
